UNITED STATES PATENT OFFICE.

LOUIS E. F. WACHTER, OF NEW YORK, N. Y.

WATCH.

1,314,172.

Specification of Letters Patent. Patented Aug. 26, 1919.

Application filed May 13, 1919. Serial No. 296,774.

To all whom it may concern:

Be it known that I, LOUIS E. F. WACHTER, a citizen of the United States, residing at New York, in the county of New York and 5 State of New York, have invented certain new and useful Improvements in Watches, of which the following is a specification.

My invention relates to certain new and useful improvements in watch bows, and 10 also to the means of pivoting the watch bow to the pendant, and the principal object of my invention is to produce a construction in which the winding stem of a watch is more easily accessible when the bow 15 is turned down than with the ordinary construction, and also to provide that the body of the bow shall extend in substantially the plane of the axis of the pendant when the bow is in its extended position.

20 A further object of my invention is to provide a construction in which the bow may be caused to lie flat against the back of the case of a watch when turned back.

25 A further object of the invention is to provide a form of bow which will not, if its spring tension is too strong, crush in the sides of the crown portion of the pendant, due to the fact that the portion of the pendant between the ends of the bow can 30 be and preferably is made solid.

With the foregoing and other objects in view my invention consists in certain constructions, arrangements and combination of parts, several forms of which will be first 35 described in connection with the accompanying drawing, and then the invention particularly pointed out in the appended claims.

Referring to the drawing wherein the same part is designated by the same reference numeral wherever it occurs,

40 Figure 1 is a perspective view of a portion of the back of a watch fitted with one form of my invention;

Fig. 2 is an edge view of the construction 45 shown in Fig. 1;

Fig. 3 is a view similar to Fig. 2, showing however the bow folded back and resting against the back case of the watch;

Fig. 4 is a view illustrating a modified 50 shape of bow, and a modified form of lug on the pendant to which the bow is pivoted.

Fig. 5 is an edge view of the construction shown in Fig. 4;

Fig. 6 is a partial section of another form 55 of construction in which the bow is pivoted to the lug on the pendant by a pivot pin ex-

tending through both the lug and the ends of the bow;

Fig. 7 is a detail perspective view of the ring encircling the pendant in the form 60 shown in Fig. 6;

Fig. 8 is a perspective view of another modification in which however a pivot pin is used as in Fig. 6;

Fig. 9 is a sectional top view of the construction shown in Fig. 8.

10 designates an ordinary watch case provided with a pendant 11 of any ordinary or desired construction, and 12 indicates the ordinary winding stem. The pendant 11 in accordance with my invention is provided with a projecting lug on the side adjacent to the back of the watch, as best shown in Fig. 1, which lug may be of various forms, as illustrated in the various figures. In Figs. 1 and 2 this lug is indicated by 13, and is generally cylindrical. In the form shown in Figs. 4 and 5 this lug is designated at 14, and is shown as generally rectangular. In Fig. 6 the lug is indicated at 15, and is generally rectangular but mounted upon a sleeve 16 surrounding the pendant 11. In Figs. 8 and 9 the lug is shown as formed integral with the pendant and of general cylindrical outline, and is 75 indicated by the numeral 16.

18 designates a bow the body portion of which may have any desired contour, that shown in Figs. 1, 2 and 3 being generally heart shape with the outer end 19 slightly 90 bent to stand up from the back of the case when the bow is folded down, as indicated in Fig. 3. In the remaining figures the bow is of the general circular outline most commonly employed.

95 In accordance with my invention the end portions of the bow are bent at 20 so that the ends extend at substantially a right angle to the plane of the body portion of the bow. The length of the turned up end portion is such 100 that when the ends are pivoted in the lugs on the pendant the body portion of the bow will be in substantially the plane of the axis of the pendant when the bow is in its extended position.

105 In the form of construction shown in Figs. 1 to 5 inclusive the ends of the bow simply snap into depressions in the ends of the lugs 13 and 14. In the form shown in Figs. 6 to 9 inclusive however a hole is drilled 110 through the ends of the bow and the blocks 15 or 17 and a pin passed through the open-

ings and riveted at its ends. By this construction the bow can be positively secured in place, this being another advantage in the use of the offset lug.

5 I realize that considerable variation is possible in the details of construction and arrangement of parts without departing from the spirit of my invention, and I therefore do not intend to limit myself to the 10 specific form shown and described.

Haying thus described my invention what I claim as new and desire to secure by Letters Patent is:

1. The combination with a pendant, of a 15 bow pivoted to the pendant at a point outside the plane of the axis of the pendant, the ends of the bow being so extended that the body portion thereof is in substantially the plane of the axis of the pendant when the 20 bow is in its extended position.

2. The combination with a pendant, of a bow pivoted to the pendant at a point outside the plane of the axis of the pendant

with the ends of the bow extending at an angle to the plane of the body portion 25 thereof.

3. The combination with a pendant provided with a lug on one side thereof, of a bow having its ends extending at an angle to the plane of the body portion thereof and 30 pivoted to said lug.

4. As a new article of manufacture, a watch bow having its ends extending at an angle to the plane of the body portion thereof.

5. As a new article of manufacture, a watch bow having its ends extending at substantially a right angle to the plane of the body portion thereof.

In testimony whereof I affix my signature 40 in presence of two witnesses.

LOUIS E. F. WACHTER.

Witnesses:

JOHN DARBY,
CHARLES C. BRESEE.
